C. R. WALDRON ET AL

BATHING SHOE OR SLIPPER

Filed Sept. 29, 1922

FIG. 1

FIG. 2

CHARLES R. WALDRON, INVENTORS
STEPHEN G. STEVENSON

BY *Rickey Slough & Watta*

HIS ATTORNEY'S.

UNITED STATES PATENT OFFICE.

CHARLES R. WALDRON AND STEPHEN G. STEVENSON, OF ELYRIA, OHIO.

BATHING SHOE OR SLIPPER.

Application filed September 29, 1922. Serial No. 591,225.

To all whom it may concern:

Be it known that we, CHARLES R. WALDRON and STEPHEN G. STEVENSON, citizens of the United States, and residents of 5 Elyria, in the county of Lorain and State of Ohio, have invented a certain new and useful Improvement in Bathing Shoes or Slippers, of which the following is a specification.

10 This invention relates to bathing shoes, or slippers, and especially to such devices having an enlarged toe to assist the wearer when swimming.

An object of this invention is to construct 15 a shoe or slipper, with an enlarged flat toe which is light and retains its shape when used for swimming.

Another object resides in providing a 20 light fabric swimming shoe with an enlarged toe which is held in shape by a stiff reinforcing element extending around the edge thereof.

Another object of my invention embodies 25 the details of construction, and the manner in which the shoe is assembled.

In the drawings, Fig. 1 is a top plan view 30 of the shoe having a portion of the toe cut away and in section. Fig. 2 is a side elevation of our shoe.

Referring to the drawings, the shoe or 35 slipper is made up of an enlarged toe portion and a heel portion, both of which are constructed preferably of a water-proof light fabric material, such as canvas.

The toe is wide and of sufficient length 40 to present a flat surface of considerably more area, than the area of the wearer's foot upon which it is secured, and in this manner aids the wearer when swimming.

The toe of the shoe, or slipper, is formed 45 of a canvas sole 10 and a vamp 11, which are superimposed and of substantially the same configuration. The edges of the sole and vamp can be sewed together, and as shown, the vamp is of sufficient size to allow 50 its edges to be bent over and sewed to the edge of the sole at 12. When connecting the two parts of the toe in this manner, we thereby provide a hollow enclosure 13

55 within the two members and around the periphery thereof, to receive a stiff frame 14, preferably wire, which serves to reinforce the toe and retain it in shape under all conditions. The vamp and sole are also sewed together at 15 to provide a snug inclosure

for the toes of the wearer, and also, to reinforce the inner area of the toe of the shoe.

A heel, or upper, 15 having an open top and bottom extends forwardly and is sewed to the vamp at 16. The usual eyelets 17 60 and lace 18 are provided in the forward extension to secure the shoe to the wearer's foot.

Tabs 19 are sewed on each side of the heel, or upper, and the ends 20 of the wire 65 frame 14 projecting rearwardly from the toe extend upward between the tabs and the heel. This arrangement retains the toe in a horizontal flat position.

When the lace is loosened the wearer puts 70 the shoe on in the usual manner, with his toes between the vamp and the sole and within the space within the stitching 15; his heel extends through the open bottom of the heel which is secured around the ankle 75 by the lace 18.

The mode of operation and advantages 80 incident to the particular form and construction of the shoe are believed to be obvious, and to render further description unnecessary.

Various modifications of our invention 85 may be devised by those skilled in the art, without departing from the spirit of the invention and the scope of our claims, and we therefore do not limit our invention to the exact construction disclosed.

What we claim is:—

1. A swimming shoe comprising an enlarged toe formed of a sole and a vamp secured together, and a wire frame secured adjacent the periphery of said toe between the sole and the vamp thereof. 90

2. A swimming shoe comprising an enlarged toe, an upper secured to said toe, and a wire frame secured adjacent the periphery of and to said toe, the ends of said frame extending rearwardly and upwardly from said toe and having their ends connected to the sides of said upper. 95

3. A swimming shoe comprising an enlarged toe formed of a sole and a vamp sewed together, an upper adapted to be secured to a user's ankle, a wire frame for said toe, the ends of said wire frame extending rearwardly from said toe to said upper, and means to secure the ends of said wire frame to said upper. 105

4. A swimming shoe comprising an enlarged fabric sole, a wire reinforcing frame 110

extending around the peripheral portion of said sole and secured thereto, a vamp, and means for securing said sole to a user's foot.

5. A swimming shoe comprising an enlarged toe formed of a sole and a vamp, an upper secured to the rear end of said toe, and a stiff frame between said sole and vamp extending around the periphery thereof, said sole and vamp being sewed together interiorly of said frame.

6. A swimming shoe comprising an enlarged fabric vamp, a wire frame attached to and extending substantially around the periphery of said vamp, said frame being adapted to maintain said fabric vamp stretched interiorly thereof, and means for

securing said vamp upon the top of a user's foot.

7. A swimming shoe comprising an enlarged fabric vamp, a wire frame attached to the peripheral portion of said vamp, a sole secured to said vamp providing an intermediate space for the insertion of a portion of a user's foot, and means for securing said shoe to a user's foot when inserted partially within the space intermediate said sole and said vamp.

In testimony whereof, we hereunto affix our signatures.

CHARLES R. WALDRON.
STEPHEN G. STEVENSON.
